UNITED STATES PATENT OFFICE.

HARRY GLAENZER AND JOHN S. KEEN, OF PHILADELPHIA, PENNSYLVANIA, AS
SIGNORS TO THE BALDWIN LOCOMOTIVE WORKS, OF PHILADELPHIA, PENNSYLVANIA, A CORPORATION OF PENNSYLVANIA.

RAILWAY TRUCK.

Application filed May 11, 1925. Serial No. 29,429.

To all whom it may concern:

Be it known that we, HARRY GLAENZER and JOHN S. KEEN, citizens of the United States, residing in Philadelphia, Pennsylvania, have invented a Railway Truck, of which the following is a specification.

A railway truck embodying the invention is applicable to cars and locomotives, particularly electric locomotives, and it will be understood that the term "car" as used herein is to be construed broadly as also covering locomotives and other equivalent or similar constructions.

The principal object of the invention is to provide a railway truck for locomotives and the like having a simple and rugged construction and provided with improved means for supporting the bolster from the main truck frame. Further objects of the invention will be apparent from the following specification and claims.

In the accompanying drawings we have shown the embodiment of the invention which we now deem preferable but it will be understood that the drawings are for illustrative purposes only and that various changes and substitutions may be made within the scope of the claims without departing from the spirit of the invention.

Of the drawings:

Fig. 1 is a plan view of a truck embodying the invention.

Fig. 2 is a longitudinal sectional view taken along the line 2--2 of Fig. 1.

Fig. 3 is a fragmentary longitudinal sectional view taken along the line 3--3 of Fig. 1.

Fig. 4 is a vertical transverse sectional view taken along the line 4--4 of Fig. 2.

Fig. 5 is a fragmentary longitudinal sectional view taken along the line 5--5 of Fig. 1.

Fig. 6 is a detailed view of one of the supporting links.

Referring to the drawings, 1, 1 are the main side members of the truck frame, these being each provided with two recesses at 2, 2 for axle journal boxes and with a large central recess at 3 for a spring. A tie member 4 extending along the bottom of each side member connects together and reinforces the several parts of the side member proper. The two side members 1, 1 are connected at their ends by transverse tie

bars 5, 5. Positioned in the recesses 2, 2 in the usual manner are axle journal boxes 6, 6 which are capable of a limited amount of vertical movement without engaging the frame at the tops of the recesses or engaging the tie member 4 at the bottoms of the recesses. The axle boxes are supported on the usual axles 7, 7 which are connected with track wheels 8, 8.

Extending longitudinally at opposite sides of each of the main side members 1, 1 are bridge members 9, 9, which rest directly on the journal boxes 6, 6. Located in the recess 3 and between the two bridge members 9, 9 is a spring 10, preferably of the leaf type which is carried by the said bridge members. Preferably there are two links 11, 11 provided for this purpose, and each of these links is connected with the two bridge members by means of a bearing pin 12. The pins 12 serve not only to support the links but also to connect the two bridge members together to form a unitary structure. The spring 10 is provided with apertures near its ends through which the respective links 11 extend; and the spring rests at its ends on shoe plates 13, 13 which are also apertured for the links 11, 11. Pins 14, 14 extend transversely through apertures in the links and engage seats formed in the bottoms of the plates 13, 13. As the result of this construction, each spring is flexibly carried by the corresponding bridge members 9, 9.

As shown most clearly in Fig. 3, each side member of the frame is provided with a spring seat 15 which is adapted to receive the upper end of a bearing member 16 carried by the spring 10. Preferably this bearing member also serves as a spring clip, being provided with a recess through which the several leaves of the spring pass. Preferably the upper end of the bearing member 16 is slightly convex so as to provide a certain degree of flexibility. From the foregoing description it will be clear that the springs 9, 9 serve to resiliently support the truck frame in such a way as to permit any one of the axle journal boxes to move independently of the others and independently of the frame to accommodate irregularities in the road bed.

The bolster support is shown at 17 and this extends entirely across the frame, being

rigidly connected by bolts or otherwise to the tops of the side members 1, 1. The bolster support 17 has two similar transverse elements 18, 18 which are separated to provide 5 a large transversely extending recess 19 between them. Preferably the elements 18, 18 are connected together at the bottom below the recess by a tie 20 as shown in Fig. 2.

Located in the recess 19 is a bolster 21 10 which is supported from the bolster support by means of four links 22, 22. The bolster 21 has transverse vertical guide surfaces 23 which are adapted to engage similar surfaces 24 on the interior of the recess 19 in 15 the bolster support 18. The bolster has a loose fit in the recess but the said guide surfaces serve to prevent any considerable relative longitudinal movement of the bolster, without interfering with lateral movement. 20 Each of the links 22, 22 is located in a short transversely extending pocket 25 in one of the transverse elements 18 of the bolster support and it is connected therewith by means of two pins or bolts 26, 26. The links 25 22, 22 are pivotally connected with the bolster 21 by means of longitudinally extending pivot pins 26^a, 26^a. As shown most clearly in Figs. 4 and 6, each link engages the corresponding bolts or pins 26 only at the tops 30 thereof, being cut away below the pins to form a recess 27. It will be clear, therefore, that each link 22 is normally held by gravity in engagement with both of the pins 26, but that upon the application of lateral pressure 35 can be moved about the axis of either pin. This means of supporting the bolster 21, therefore, serves to normally hold the bolster in its normal central position as shown, but in service a slight lateral movement of 40 the bolster can take place to eliminate severe strain and shock. After such lateral movement, however, the bolster is quickly returned by gravity to its normal central position.

45 The bolster 21 is provided at its center with a socket 28 which is adapted to receive a pivot boss 29 depending from the body of the locomotive or car. It will be clear that the socket 28, together with the pivot 50 boss 29, constitute a pivotal connection between the truck and the locomotive or car body. Preferably as shown, the socket 28 is provided with a liner 30 which is slightly convex in vertical section so as to permit a 55 limited amount of side sway of the car or a limited amount of relative rocking of the truck without causing binding or clamping.

At the respective ends of the bolster 21 are 60 seats 31, 31 which are adapted to engage and support the equalized spring structure of the locomotive or car. It will be observed that these seats are approximately vertically above the pivotal axes of the respective pairs of supporting links 22, 22. The spring structure is indicated at 32 but is not de-

scribed in detail, as it is or may be of any usual or preferred construction and does not constitute any part of our present invention. It will be understood that the pivot boss 29 is free to move vertically in 70 the socket 28 to accommodate the action of the spring mechanism 32.

What we claim is:

1. In a railway truck, the combination 75 with the truck wheels, the axles, the journal boxes and the main frame, of means for supporting the main frame on the said boxes, a transverse bolster support extending across the main frame and comprising two transverse members with a transverse recess between them, a bolster located in the said recess and adapted to support a car body, two pairs of links respectively located at opposite sides of the center of the truck and connected with the respective transverse 80 members and serving to support the bolster on the bolster support while permitting it to move laterally in the said recess, and two pivot pins at one end of each link and engaging it only at their outer sides so that 85 pivotal movement can take place about either of them.

2. In a railway truck, the combination 90 with the truck wheels, the axles, the journal boxes and the main frame, of means for supporting the main frame on the said boxes, a transverse bolster support extending across the main frame and comprising two transverse members with a transverse recess between them, a bolster located in the said recess and adapted to support a car body, two pairs of links respectively located at opposite sides of the center of the truck and connected with the respective transverse 95 members and serving to support the bolster on the bolster support while permitting it to move laterally in the said recess, two pivot pins at the respective ends of the bolster and extending through it to engage the two links of the respective pairs, and two pivot pins for each link carried by the corresponding transverse member and engaging the said link only at their lower sides so that pivotal movement can take place 100 about either of them.

3. In a railway truck, the combination 105 with the truck wheels, the axles, the journal boxes and the main frame, of means for supporting the main frame on the said boxes, a transverse bolster support extending across the main frame and comprising two transverse members with a transverse recess between them, each member having two pockets formed therein at opposite sides of the center of the truck, a bolster located in the said recess and adapted to support a 110 car body, pivoted links located in part in the respective pockets and serving to support the bolster on the bolster support while permitting it to move laterally in the said recess, 115

and two pivot pins at one end of each link and engaging it only at their outer sides so that pivotal movement can take place about either of them.

6. In a railway truck, the combination with the truck wheels, the axles, the journal boxes and the main frame, of means for supporting the main frame on the said boxes, a transverse bolster support extending across 10 the main frame and comprising two transverse members with a transverse recess between them, each member having two pockets formed therein at opposite sides of the center of the truck, a bolster located in 15 the said recess and adapted to support a car body, pivoted links located in part in the respective pockets and serving to support the bolster on the bolster support while permitting it to move laterally in the said recess, and two pivot pins extending through 20 each pocket and engaging the corresponding link only at their outer sides so that pivotal movement can take place about either of them.
25. 5. In a railway truck, the combination with the truck wheels, the axles, the journal boxes and the main frame, of means for supporting the main frame on the said boxes, a transverse bolster support extending across 30 the main frame and comprising two transverse members with a transverse recess between them, the transverse walls of the recess being vertical and parallel, a

bolster located in the said recess and adapted to support a car body, the surfaces of 35 the bolster approximately fitting between the transverse walls of the recess, pivoted links serving to support the bolster on the bolster support while permitting it to move laterally in the said recess, and two pivot pins at one end of each link and engaging 40 it only at their outer sides so that pivotal movement can take place about either of them.

6. In a railway truck, the combination with the truck wheels, the axles, the journal boxes and the main frame, of means for supporting the main frame on the said boxes, a transverse bolster support extending across 45 the main frame and comprising two transverse members with a transverse recess between them, a bolster located in the said recess and adapted to support a car body, links located at opposite sides of the center 50 of the truck and pivotally connected to the bolster support and bolster, the said links serving to support the bolster on the bolster support while permitting it to move laterally in the said recess, and seats for a car body supporting mechanism respectively 55 located approximately vertically above the axes of the pivotal connections between the links and the bolster.

HARRY GLAENZER.
JOHN S. KEEN.
